[57] **CLAIM**

An ornamental design for a square brim sun visor, as shown and described.

DESCRIPTION

FIG. 1 is a perspective view of the square brim sun visor showing my new design.

FIG. 2 is a top plan view thereof.

FIG. 3 is a side elevation thereof.

FIG. 4 is a sectional view taken at line 4—4 of FIG. 2.

FIG. 5 is a sectional view taken at line 5—5 of FIG. 2.

FIG. 6 is a side elevational view of my square brim sun visor in operative condition.

FIG. 7 is a top plan view of a square brim sun visor showing a second embodiment of my design.

FIG. 8 is a top plan view of a square brim sun visor showing a third embodiment of my design.

FIG. 1

FIG. 2
